UNITED STATES PATENT OFFICE

127,979

DESIGN FOR A BEVERAGE DISPENSING CONTAINER

John M. Travis, St. Louis, and Bernard F. McMahon, St. Louis County, Mo., assignors to Multiplex Faucet Company, St. Louis, Mo., a corporation of Missouri

Application April 29, 1941, Serial No. 100,700

Term of patent 7 years

To all whom it may concern:

Be it known that we, John M. Travis and Bernard F. McMahon, citizens of the United States, residing respectively in the city of St. Louis, State of Missouri, and St. Louis County, State of Missouri, have invented a new, original, and ornamental Design for a Beverage Dispensing Container, of which the following is a specification, reference being had to the accompanying drawing, forming a part thereof.

We claim:

The ornamental design for a beverage dispensing container, as shown.

JOHN M. TRAVIS.
BERNARD F. McMAHON.
